MANIFOLD FOR TUBULAR DRIERS

Adolph W. Lissauer, Louisville, Ky., assignor to
Louisville Drying Machinery Co., Louisville,
Ky.

Application June 6, 1934, Serial No. 729,179

2 Claims. (Cl. 257—92)

My invention relates to manifolds for driers of the type disclosed in Patent No. 1,139,663 of May 18, 1915, and has reference more particularly to a fabricated unit as distinguished from a cast iron one.

The object of the invention is to provide a manifold which is suitable for pressures for which a cast iron manifold is not suited, and also to provide passages which offer less resistance to flow, both in cross-sectional area and wall texture.

Another object of the invention is to provide a manifold, the generic features of which are suitable for both high and low pressure driers.

With these and other objects in view, my invention consists in the combination of parts shown in the accompanying drawing and described in the specification, and more particularly pointed out in the claims.

In the appended drawing, Figure 1 is a fragmentary elevation of a manifold for high pressure, embodying my invention. A portion of same has been broken off to show the details of construction.

Figure 2 is a section on line 2—2, Figure 1, and Figure 3 is an elevation of a bucket for a manifold to be used for low pressure.

Referring to the drawing, the manifold comprises a dished member or section 5 and a disc member or section 6 located within the dished member but spaced from the bottom of same by stay bolts 10 which connect the two members together. The stay bolts provide the necessary clearance between the members 5 and 6 of the manifold to accommodate therebetween a plurality of scoops 7 spaced equi-angularly through the radial area in accordance with the number of scoops used. As shown in the drawing, three such scoops are provided in this particular structure.

Each scoop has a scooping wall 8 extending across the entire radial distance of the manifold, said wall extending or continuing into a retaining wall 9 from substantially the central part of the manifold, the two walls 8 and 9 diverging as their distance from the center of the manifold increases. The retaining wall 9 stops short of the openings for the inner circle of the tubes. Preferably, the walls 8 and 9 of the scoop are united by side walls 11, so that the scoop forms a unit that may be introduced between the members 5 and 6 of the manifold.

At the juncture of the walls 8 and 9, a nipple 12 is provided in one of the side walls 11 to pass through the bottom of the dished member 5.

In addition, the two members 5 and 6 have

tubular members 13 passing therethrough but not connected with the inner space 14 formed by spacing the two members 5 and 6. These tubular members provide air for drying into the interior of the drier and also access in case of tube replacement.

As shown in Figures 1 and 2, when the manifold revolves clockwise, the steam supplied through tubes fitting the openings 16 and 17 passes out into the manifold as condensate that accumulates in the bottom of any of the spaces 14 formed between the walls 8 of any of the adjacent scoops, and it is forced, due to the rotation, to travel with said wall until gravity moves the condensate toward the narrower end of the scoop. As the scooping wall 8 approaches the vertical plane, the quantity of condensate converging toward the nipple increases, due to the convergency toward the nipple of the scooping and retaining walls 8 and 9. In consequence of that, the entrapped condensate is able to build up a hydrostatic head which facilitates the discharge of the condensate through the nipple 12.

As shown in Figures 1 and 2, the structure is designed for high pressure steam. For lower steam pressure driers the distance between the members 5 and 6 is materially increased. The divergence between the walls 8 and 9 is retained, same as shown in Figures 1 and 2, but in lieu of having parallel walls 11, the walls 11' in which the nipple 12' is located is parallel with the bottom of the dished member 5, but the wall 15 opposite the wall 11', which is in proximity of the member 6 is converging toward the nipple from where it meets the retaining wall 9'. As will be seen from Figure 3, the scooping wall 8' extends similarly through the entire radial distance of the manifold unit.

From the above description, it will be seen that the scooping units divide the space between the two members into angular chambers and the accumulation of condensation of each of the chambers is discharged through the scoop lying within that chamber. It is understood that the retaining wall of the scoop lies in the said chamber, from which it discharges the condensation.

I claim

1. In a manifold of the class described, a dished member and a disc shaped member, a plurality of scoops disposed between said members and dividing the space therebetween into separate angular chambers, each chamber having a corresponding scoop, each of said scoops having a wall running substantially through the radial distance of said manifold, and a wall running

through a portion of the radial distance of the manifold and diverging from said first mentioned wall as the distance of said walls from the center of the manifold increases.

5 2. In a manifold of the class described, a dished member and a disc shaped member and a plurality of scoops disposed between said members, each of said scoops having a scooping wall adapted to run substantially through the radial distance of said members and form a separating wall

within the space between said members, said scoop having also a retaining wall forming a continuation of said scooping wall and adapted to run through a portion of the radial distance of the manifold, and diverging from said scooping wall as the distance from the said walls from the center of the manifold increases, said scoops having also side walls uniting the scooping and retaining walls to each other. 5

ADOLPH W. LISSAUER. 10
